UNITED STATES PATENT OFFICE.

JOSEPH BACHRACH, OF NEW YORK, N. Y.

MOISTENER.

Application filed March 19, 1925. Serial No. 16,625.

To all whom it may concern:

Be it known that I, JOSEPH BACHRACH, a citizen of the United States, and a resident of New York, in the county of New York and State of New York, have invented certain new and useful Improvements in Moisteners, of which the following is a specification.

This invention relates to moisteners, and more particularly to a simple, inexpensive and serviceable device for moistening the gummed surface of an envelope closure flap or other articles.

It is one of the important objects of my present improvements to provide a device of the above character which is provided with adjustable means for regulating the feed of water to an applying member movable over the gummed surface.

More particularly, in one simple and practical embodiment of the device, I provide a tubular container for the water contracted at one end and provided with a pocket to receive a suitable absorbent material and a non-absorbent distributing roller removably mounted beneath said pocket and engaging the absorbent material to apply the water to the gummed surface of the envelope flap. The other end of the water container is provided with an airtight closure plug and an adjustable valve member carried by said plug whereby the ingress of air to said container may be regulated. Thus, the air pressure upon the body of water tending to force the same through the absorbent material in said pocket may be varied to control the supply of water to the surface of the distributing roller.

With the above and other objects in view, the invention consists in the improved moistener and in the form, construction and relative arrangement of its several parts as will be hereinafter more fully described, illustrated in the accompanying drawing and subsequently incorporated in the subjoined claims.

In the drawings, wherein I have illustrated one simple and practical embodiment of the invention, and in which similar reference characters designate corresponding parts throughout the several views,—

Figure 1 is a perspective view illustrating the manner of using my improved moistener;

Fig. 2 is a longitudinal sectional view 55 through the moistener on an enlarged scale showing one position of the adjustable air valve;

Fig. 3 is a fragmentary sectional view illustrating another position of said valve: 60

Fig. 4 is a detail elevation of the air valve;

Fig. 5 is a horizontal section taken on the line 5—5 of Fig. 4;

Fig. 6 is a fragmentary elevation partly in section showing the mounting of the water 65 distributing roller;

Fig. 7 is an end elevation thereof;

Fig. 8 is a detail elevation of one of the parts; and

Fig. 9 is a detail view illustrating an 70 alternative form of the valve means.

Referring in detail to the drawings, for purposes of illustration, I have shown an elongated water container 5 which may be conveniently produced from light sheet 75 metal and for substantially one-half of its length is of cylindrical form, the remaining longitudinal portion of the container being contracted as indicated at 6, and providing opposite flattened side portions 7. This contraction and flattening of the tubular container produces a widened end thereof which slightly exceeds the diameter of the cylindrical portion of said container and the flattened side walls 7 at said widened end are 85 bent or formed to provide outwardly projecting flanges or shoulders 8 and then extended in parallel relation to each other as at 9, thereby forming a pocket 10 open at its lower side and adapted to receive a strip of 90 felt or other suitable water absorbent material 11. The opposite end walls of said pocket are extended beyond the edges of the side walls thereof to provide ears 12.

Between the ears 12, a water distributing 95 member is mounted. As herein shown, this member consists of a roller 14 of non-absorbent material which is provided with a multiplicity of spaced circumferential grooves 15 in its surface. This roller is 100 loosely mounted for free rotation on a rod 16 engaged through apertures in the ears 12.

One of these ears is provided on one edge thereof with the flange or extension 12' having a notch or seat 12^a therein. One end of the rod 16 is bent at right angles as at 16' and the terminal thereof is inwardly bent or extended and formed into a hook 16^a as shown in Fig. 8 of the drawings. After the rod 16 is engaged through the apertures of the ears 12 and the bore of the roller 14, the rod is then turned so that the hook 16^a thereof rides upon the rounded end edge of one of the ears 12 and snaps into the recess or seat 12^a in the flange 12', thereby releasably holding the rod against turning movement. It will be understood that this hooked end 16^a of the rod is sufficiently yieldable or resilient to permit of the same being disengaged from the notch or seat 12^a so that the rod 16 and roller 14 can be easily removed for the purpose of renewing the absorbent material 11 when necessary.

The open end of the cylindrical portion of the container 5 is provided with a water and air-tight closure. This closure as herein shown is preferably in the form of a soft rubber plug 18. This plug is provided with a central opening 19 to receive an adjustable air valve 20. This valve may be of various constructions, but I have illustrated a very simple form of valve consisting of a cylindrical stem adapted for insertion through the opening 19 in the plug. This stem at one of its ends is diametrically enlarged as at 21 so that in order to insert the stem through the opening 19, considerable pressure must be applied and thereby expand the rubber plug, momentarily enlarging the opening 19 as the valve stem is forced therethrough. When this enlarged end 21 is projected beyond the inner end of the opening 19, said plug will resume its former condition and the wall of the opening 19 will closely engage upon the periphery of the valve stem, and thereby prevent the entrance of air between said valve stem and the plug to the interior of the container.

The outer end portion of the valve stem 20 is also diametrically enlarged and may be provided with annular corrugations indicated at 22 to provide a gripping surface for the fingers. This end of the valve stem is also provided with an axially extending bore 23 open at its outer end and communicating at its inner end with a transverse orifice 24, said orifice constituting a continuation of a longitudinally extending groove 25 formed in the outer surface of the valve stem. This groove gradually decreases in width and depth from the orifice 24 to the inner end of the valve stem where it merges into the peripheral surface thereof adjacent the enlarged end 21.

From the above description, the construction and manner of operation of the device will be readily understood. Assuming that

the container 5 has been filled with water and a felt strip or other absorbent material 11 of relatively close texture arranged in the pocket 10, when the valve 20 is in the position shown in Fig. 3 of the drawings to entirely exclude air from the interior of the container 5, there will be little or no seepage of the water through the felt material 11 to the surface of the roller 14. When it is desired to use the device, the valve 20 is forced inwardly as indicated in Fig. 2 so that the inner end of the groove 25 will communicate with the interior of the container, thus admitting air thereto through said groove, the port 24 and the bore 23 of the valve member. Since the groove 25 varies in area longitudinally of the valve stem, it will be apparent that by proper adjustment of this valve stem, the volume of air entering the container may be regulated, thus varying the pressure of air upon the body of water in the container and regulating the feed of water through the absorbent material to the roller 14.

The cylindrical end portion of the water container may be grasped by the hand in the manner indicated in Fig. 1 and the roller 14 drawn over the gummed surface of the envelope flap. Thus the water seeping through the material 11 to the surface of said roller will be more or less uniformly distributed by the circumferential grooves 15 in said roller to the gummed surface. In this manner, the gummed surfaces of the envelope flaps may be very rapidly moistened and the envelopes sealed. After using the device, the valve stem 20 is pulled outwardly to the position shown in Fig. 3, thus cutting off the feed of water to the roller 14 so that there will be practically no loss through evaporation.

In Fig. 9 of the drawings, I have illustrated another form of valve means for regulating the supply of air to the container and which by reason of its simplicity and low cost of production, may be considered preferable. As shown, the wall of the container 5 adjacent its open end is provided in one side thereof with a circumferentially extending slot 26 which is gradually tapered or reduced in width from one end to the other thereof. In this case, the rubber plug 18' is provided in its periphery with a longitudinally extending groove or channel 27. It will be obvious, that after the plug has been inserted into the open end of the container to close the same, that by rotating said plug, the groove 27 therein may be placed in registration with different portions of the slot 26 to thereby regulate the volume of air entering the container through said slot and the groove 27.

In the foregoing description, I have described an embodiment of the invention which has given excellent service in prac-

tical use, nevertheless it will be understood that the essential features of my present disclosure might also be incorporated in various other alternative constructions and I accordingly reserve the privilege of adopting all such legitimate changes therein as may be fairly embodied within the spirit and scope of the invention as claimed.

I claim:

- 10 1. A moistener comprising a water container having a constricted end portion terminating in a pocket of greater cross sectional area than the adjacent constricted portion and providing shoulders in the opposite side walls of the container, said pocket having unobstructed communication with the interior of the container and being open at its lower side, an absorbent material in said pocket, and a detachably mounted water distributing roller directly engaging said absorbent material at the open side of the pocket and constituting means for removably retaining the same therein in contacting engagement against said shoulders.
- 20 2. A moistener comprising a water con-

tainer having a pocket at one of its ends in unobstructed communication with the interior of the container, the lower side of said pocket being open and the end walls thereof provided with longitudinally extending perforated ears projecting beyond the open side of said pocket, one of said ears having a cam edge and a seat at one end thereof, a water absorbent material in said pocket, a water distributing roller arranged between 35 said ears and removably retaining the absorbent material in the pocket, and means for detachably and rotatably supporting said roller in operative position consisting of a rod extending axially through said roller and through the perforations in said ears, one end of said rod being angularly bent and having a terminal part adapted to coact with said cam edge of the ear when said rod is turned in one direction to be 40 releasably engaged in said seat.

In testimony that I claim the foregoing as my invention, I have signed my name hereto.

JOSEPH BACHRACH.
